Frank S. Greene,

ATTORNEY

UNITED STATES PATENT OFFICE

DANIEL K. POPE, OF CLEVELAND, OHIO

SPRING COVER

Application filed July 7, 1928. Serial No. 291,026.

The present invention relates to a detachable cover and lubricator for leaf springs such as are employed for supporting a vehicle body, and has for its object to provide a flexible cover which can be quickly and easily attached to a spring or detached therefrom and which is so constructed as to maintain a tight joint along the attached edges of the cover.

10 A further object is to provide a cover having reinforced edges to which the fastening elements are attached, the reinforcement providing a rigid anchor for the fastening elements and being flexible longitudinally so 15 as to conform to the bowed surface of the spring to which the cover is applied.

A further object is to provide fastening elements at intervals along the edges of the cover by means of which the cover may be 20 drawn tightly around the spring and which may be locked in adjusted positions to securely hold the edges of the cover together.

A further object is to provide a fastening element in the form of a projecting sheet 25 metal tongue attached to one edge of the cover and an eye formed to receive the tongue attached to the opposite edge so that the tongue may be passed through the eye and pulled to draw the edges of the cover together 30 and to provide means in connection with the tongue for securely clamping the outer end portion of the tongue against the inner end thereof to lock the fastener.

With the above and other objects in view, 35 the invention may be said to comprise the spring cover as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of the specification in which:

45 Figure 1 is a fragmentary side elevation of a spring with the cover thereon, a portion of the cover being broken away to show the structure of the cover; Fig. 2 is a section taken on the line indicated at 2-2 in Fig. 1; Fig. 3 is a plan view of the cover in open

position; Fig. 4 is an end view of the cover in open position; Fig. 5 is a section taken on the line indicated at 5-5 in Fig. 3; Fig. 6 is a section taken on the line indicated at 6-6 in Fig. 3; Fig. 7 is a bottom plan view showing the spring with the cover in place thereon; Fig. 8 is a perspective view of one of the fastener tongues; Fig. 9 is a perspective view of one of the fastener eyes; Fig. 10 is a plan view of a reinforcing strip; and Fig. 11 is a section taken on the line indicated at 11-11 in Fig. 10.

Referring to the accompanying drawings, the cover of the present invention is shown applied to an automobile spring 1 composed of superposed leaves of progressively shorter length, the cover 2 being formed of flexible material such as water proof fabric and being of substantially trapezoidal shape so that it may be wrapped about the spring with its opposite side edges adjoining along the bottom of the spring.

The cover preferably has a felt lining 3 and is provided with relatively thick felt padding strips 4 and 5 attached to its end edges. The cover 2 serves to secure in place upon the top surface of the spring a felt pad 6 which serves as a reservoir for lubricant which works into the spaces between the leaves of the spring, the lubricant being preferably a solid or semi-solid mineral oil with which the pad is impregnated and which is wiped off the pad by the leaves during flexing of the spring and the felt lining 3 serves as a heat insulator to prevent condensation of moisture on the spring within the cover.

The cover 2 is secured tightly upon the spring with its edges adjoining along the bottom of the spring so as to prevent water from reaching the portion of the spring within the cover, the end pads 4 and 5 providing a tight joint at the ends of the cover to prevent water or dust from entering the cover through the ends.

The present invention resides in means for quickly and securely fastening the cover in place on the spring and for maintaining a tight joint between the adjoining edges of the cover. The opposite side edges of the flexible cover 2 are folded over flat reinforcing

strips 7 which are preferably formed of resilient metal and the edges of the fabric are secured inwardly of the strips 7 by means of lines of stitching 8. The felt lining 3 is preferably secured in the edge folds of the cover 2, the edges of the lining overlying the reinforcing strips 7 and one of the edges has attached thereto a flap 9 which extends into the fold and is secured in place by the stitching 8, the flap 9 extending across the space between the edges of the cover within the cover when the cover is secured in place on the spring. Sheet metal tongues 10 are attached to one of the reinforced edges of the cover and as shown in Figs. 7 and 8, each of the tongues is provided at its inner end with laterally projecting portions 11 and with an aperture 12 which receives a rivet 13 which extends through the reinforcing strip 7 and the fabric overlying the opposite sides of the reinforcing strip. Each tongue 10 projects outwardly at right angles to the edge to which it is attached and the laterally extending portions 11 lie upon the reinforced edge to which the tongue is attached and serve as locking clips as will be hereinafter explained.

Suitable eyes formed to receive the tongues 10 are attached to a reinforced edge of the cover, each eye being directly opposite a tongue. The eyes may be constructed in any suitable manner and attached by any suitable means to the reinforced edge of the cover. As illustrated herein, each eye consists of a folded sheet metal clip 14 which receives an elongated wire loop 15 of a shape to receive one of the tongues 10 and the clip 14 is secured to the edge of the cover by means of a rivet 16 which passes through the reinforcing strip 7 and the fabric overlying opposite faces of the strip.

In applying the cover to a spring, the cover is wrapped about the spring in such a manner as to bring the reinforced edges thereof along the under side of the spring. The tongues 10 are then inserted through the eyes 15 and are pulled tightly to draw the cover snugly about the spring. The tongues are then bent back upon themselves over the eyes 15 into contact with the outer surface of the inner end portions attached to the reinforced edge of the cover and are rigidly secured in this position by bending the laterally projecting portions 11 over the bent back portion of the tongue. The tongue is thus bent 180° over the eye and is positively locked against movement through the eye so that the edges of the cover are securely held against separation. The resilient reinforcing strips 7 provide a rigid anchor for the fastening elements, but are sufficiently flexible to conform to the bowed surface of the spring, the strips 7, by their resiliency acting to press the portions of the edges between the fastening elements against the under side of the spring, thus maintaining a tight joint between the edges of the

cover in the spaces between the fastening elements and providing a tight joint throughout the length of the cover with a small number of fastening elements.

These resilient strips 7 are also capable of 70 flexing with the spring and maintaining the edges of the cover in close contact therewith.

Where the spring to be covered is of considerable length, the flexing of the outer end portion of the spring may be sufficient to cause 75 a slight separation of the edges of the cover inwardly of the outer fastening element. In covers for such springs, it is desirable to provide a telescopic reinforcing strip instead of a one piece reinforcing strip. Such a telescopic strip is illustrated in Figs. 10 and 11 of the drawings in which there is shown a reinforcing strip composed of sections 17 and 18 which are telescopically connected by means of a sheet metal sleeve 19 which is attached to one of the sections by means of a rivet 20 and which is formed to slidably receive the other section. The telescopic connection shown in Figs. 10 and 11 will be in the portion of the strip which lies adjacent the outer end of the cover where the flexing of the spring is the greatest and will permit elongation of the reinforcing strip so that the strip will conform at all times to the bowed surface of the spring while it is flexing.

It will be apparent that the present invention provides a cover which can be quickly and easily applied to a spring and fastening elements by means of which the cover can be drawn into snug engagement throughout its length with the spring and by means of which the cover is securely held in tight engagement with the spring.

Furthermore, the fastening means permits the cover to be quickly detached whenever desired and re-applied to the spring. In addition, the present invention provides simple fastening devices which are spaced at intervals along the length of the adjoining edges of the cover and which serve to maintain a 105 tight joint throughout the length of the cover.

What I claim is:

1. In a cover for leaf springs composed of flexible material and of a shape to wrap about a spring with opposite edges adjoining longitudinally of the spring, a fastening device comprising a bendable sheet metal tongue having a flat inner end secured upon the outer face of the cover adjacent an edge of the cover, an eye formed to receive said tongue, said eye being aligned with the tongue and attached to the opposite edge of the cover, whereby said tongue may be passed through said eye to draw said edges together and tighten the cover on the spring and be bent back upon itself to secure the same against separation, and means for clamping the bent back end of the tongue against the flat inner end thereof.

2. In a cover for leaf springs composed of

flexible material and of a shape to wrap about a spring with opposite edges adjoining longitudinally of the spring, a fastening device comprising a bendable sheet metal tongue having a flat inner end secured upon the outer face of the cover adjacent an edge of the cover, an eye formed to receive said tongue, said eye being aligned with the tongue and attached to the opposite edge 10 of the cover, whereby said tongue may be passed through said eye to draw said edges together and tighten the cover on the spring and be bent back upon itself to secure the same against separation, and means for 15 clamping the bent back ends of the tongue against the inner ends thereof, comprising bendable sheet metal clips attached to the tongue adjacent its inner end and overlying the portion of the cover to which the inner 20 end of the tongue is attached, said clip being adapted to be bent back over the outer side of the bent back end of the tongue to secure said end upon the flat inner end of the tongue.

3. A cover for leaf springs comprised of 25 flexible material and of a shape to wrap about a spring with opposite edges adjoining longitudinally of the spring, separable tightening and fastening elements secured to the opposite edges of the cover at intervals along 30 the length thereof, resilient reinforcing bars secured in opposite edges of the cover, said bars being composed of telescopically connected sections.

4. A cover for leaf springs comprised of 35 flexible material and of a shape to wrap about a spring with opposite edges adjoining longitudinally of the spring, separable tightening and fastening elements secured to the opposite edges of the cover at intervals along the 40 length thereof, resilient reinforcing bars secured in opposite edges of the cover, said bars being of substantially flat resilient metal and being composed of sections telescopically connected between fastener elements.

45 5. In a cover for leaf springs composed of flexible material and of a shape to wrap about a spring with opposite edges adjoining along the length of the spring, a fastening device comprising a bendable sheet metal tongue 50 having a flat inner end secured upon the outer face of the cover adjacent one edge of the cover, said tongue having a laterally projecting clip formed integrally therewith adjacent its point of attachment to the cover, an eye 55 formed to receive the tongue and attached to the opposite edge of the cover, whereby the outer end of said tongue may be drawn through the eye to tighten the cover and be bent back against its inner end and said clip 60 bent over said bent back portion of the tongue to secure the same against said flat inner end.

In testimony whereof I affix my signature.

DANIEL K. POPE.
